UNITED STATES PATENT OFFICE.

FRED A. DALEY, OF CHICAGO, ILLINOIS, ASSIGNOR TO THE UNDER-FEED STOKER COMPANY OF AMERICA, OF CHICAGO, ILLINOIS, A CORPORATION OF NEW JERSEY.

STOKING MECHANISM.

SPECIFICATION forming part of Letters Patent No. 733,374, dated July 14, 1903.

Application filed April 24, 1903. Serial No. 154,142. (No model.)

To all whom it may concern:

Be it known that I, FRED A. DALEY, a citizen of the United States, residing at Chicago, in the county of Cook and State of Illinois, have invented a certain new and useful Improvement in Stoking Mechanism, of which the following is a full, clear, concise, and exact description, reference being had to the accompanying drawings, forming a part of this specification.

My invention relates to stoking mechanism, and has for its object improved construction thereof and improved disposition of the parts thereof with respect to the furnace or boiler in connection with which the stoking mechanism is utilized.

My invention is particularly adapted to so-called "underfeed-stokers," which consist of a fluid-cylinder, a ram-case or cylinder into which coal is fed from a hopper, and a retort, the retort being disposed at the inside of the boiler-chamber and the ram-case and cylinder at the outside thereof.

Heretofore it has been the practice to place the retort at the inside of the boiler-chamber, so that the front flanged face thereof was disposed to the rear of the furnace or boiler front. The ram-case, which was provided with a flange at its end, projected into an opening in the boiler-front to be bolted or otherwise fastened to the retort, the outside face of the boiler-front and the outside face of the ram-case flange being flush by such disposition.

When it was desired to inspect the interior of the ram-case, which usually consisted of a lower and an upper removable half, it was necessary after withdrawing the bolts which fastened the ram-case to the retort to move backward both the cylinder and the ram-case in order to remove the top portion of the ram-case, which in its normal position projected within the boiler-front.

My invention provides means for removing the top portion of the ram-case for the purpose of inspection without changing the position of the lower part of the ram-case, and to this end I arrange the retort within the boiler, so that the front face thereof projects into the opening in the boiler-front and flush

with the outside face of the boiler-front. The top portion of the ram-case may now be bolted in the usual manner to the retort and no impediment is offered to its ready removal from the lower portion of the ram-case. The retort has rearwardly and upwardly extending side walls, the faces of the front ends thereof being disposed to aline with the inner face of the boiler-front, which boiler-front extends downward between said faces and the upper portion of the flange on the removable ram-case section. As the removable section is bolted to the retort, the boiler-front is clamped and securely held to prevent warping thereof as it is heated.

I shall explain my invention more fully by reference to the accompanying drawings, in which—

Figure 1 is a sectional view illustrating the application of my invention to a stoker of the underfeed type. Fig. 2 is a perspective view showing the disposition and manner of assembling the ram-case parts and the retort with respect to the boiler-front. Fig. 3 is a detailed view showing the construction of the ram-case and retort at the point of junction. Fig. 4 is an end view of the retort. Fig. 5 is a side view of the forward end of the retort.

Like characters of reference indicate like parts throughout the figures.

A boiler 1 is suitably mounted upon a setting 2 and is adapted to receive heat generated in the fire-chamber 3. A retort 4 is disposed within the boiler-chamber and is adapted to receive fuel discharged therein from a ram-case 5, supplied from a hopper 6. A piston 7 is caused to oscillate in a fluid-cylinder 8 in a manner well known to those skilled in the art to reciprocate a plunger 9 within the ram-case 5. An opening 10 in the boiler-front 11 is adapted to receive the flanged end 12 of the retort, said flange being so disposed within said opening that the face 13 thereof is flush with the outside face 14 of the boiler-front. In order to make the interior of the ram-case accessible for inspection and repairs, the ram-case preferably consists of a lower portion 15 and an upper removable portion 16, said lower and upper portions having flanges 17 and 18, respectively, provided with

bolt-holes 19, whereby the two halves may be securely bolted together. The lower portion of the ram-case is provided with a downwardly-extending flange 20, adapted to be bolted against the lower portion of the front face of the retort by means of bolts 21. The upper portion of the ram-case is provided with an upwardly-extending flange 22, adapted to be secured to the upper part of the front face of the retort.

The retort has rearwardly-extending side walls 23, said walls also extending upwardly, the front faces 24 thereof being adjacent to the inside face of the boiler-front. The flange 22 of the upper portion 16 of the ram-case extends a slight distance beyond the top edge of the retort-flange, disposed within the opening 10 in the boiler-front, and as the upper portion of the ram-case is bolted into position 20 the boiler-front is clamped between the upper portion of the flange thereof and the upwardly-extending side walls of the retort disposed to the rear of the boiler-front. As the boiler-front becomes heated warping thereof 25 is prevented.

It will thus be readily seen that the ram-case is very readily accessible for inspection and repairs without moving the entire ram-case structure and the fluid-cylinder, as has heretofore been necessary, in order to gain 30 access to the ram-chamber.

Although I have described my invention as applied to stokers of the underfeed type, it is applicable to stokers of other types, and 35 changes in the structure thereof may be readily made without departing from the spirit of the invention.

I therefore claim as new and desire to secure by Letters Patent—

40 1. The combination with a furnace, of stoking mechanism associated therewith, a retort for said stoking mechanism disposed within the furnace-chamber, a charging-cylinder for said stoking mechanism disposed at the outside of the furnace-chamber for charging fuel into said retort, and means for clamping the furnace-front between said charging-cylinder and said retort, substantially as described.

45 2. The combination with a furnace, of stoking mechanism associated therewith, a front for said furnace, an opening therein, a retort for said stoking mechanism disposed within said furnace-chamber and extending rearwardly from said opening, a charging-cylinder for charging fuel into said retort disposed at the outside of said furnace, and means for clamping the front of said furnace between said charging-cylinder and said retort, substantially as described.

50 3. The combination with a furnace, of stoking mechanism associated therewith, a metallic front for said furnace, an opening in said front, a retort for said stoking mechanism extending rearwardly from said opening and 55 having a flange at its forward end, side walls on said retort extending rearwardly and upwardly, the front edge of said side walls be-

ing in alignment with the inner face of the furnace-front, a charging-cylinder for said stoking mechanism for charging fuel into said 70 retort, said cylinder being flanged at its forward end whereby it may be secured to the flanged end of the retort, the furnace-front extending downwardly between said side walls of the retort and the flanged end of said 75 charging-cylinder whereby said front is securely held in place and prevented from warping, substantially as described.

4. The combination with a furnace, of stoking mechanism associated therewith, a metallic front for said furnace, an opening in said front, a retort for said stoking mechanism extending rearwardly from said opening and having a flange at its forward end adapted to fit into and project through said opening so 80 that the face thereof is in alignment with the front face of the furnace-front, side walls on said retort extending rearwardly and upwardly, the front edge of said side walls being in alignment with the inner face of said 85 furnace-front, a charging-cylinder for said stoking mechanism for charging fuel into said retort, said cylinder terminating in a flange at its forward end whereby it may be secured to the flanged end of the retort projecting 90 through said opening, the furnace-front extending downward between said side walls of the retort and the flanged end of the charging-cylinder whereby to be securely held in place and prevented from warping, substantially as described.

5. The combination with a furnace, of stoking mechanism associated therewith, a retort disposed within said furnace for receiving fuel to be burned, and a charging-cylinder 105 for said stoking mechanism for charging fuel into said retort, said cylinder having a lower half and a top removable half, each adapted to be separately secured to said retort, said cylinder being disposed entirely at the outside of said furnace whereby the top half thereof may be removed without moving the lower half thereof, substantially as described.

6. The combination with a furnace, of stoking mechanism associated therewith, a front 115 for said furnace, an opening in said front, a retort for said stoking mechanism extending rearwardly from said opening and provided with a flange at its forward end adapted to fit into and project through said opening, a 120 charging-cylinder from which fuel is charged into said retort, a lower half and an upper removable half for said charging-cylinder, each terminating in a flange whereby to be 125 separably secured to the retort flanged and extending through said opening, said charging-cylinder being disposed entirely at the outside of the opening in said furnace-front whereby the top half thereof may be removed without moving the lower half thereof, substantially as described.

7. The combination with a furnace, of stoking mechanism associated therewith, a retort for said stoking mechanism disposed within

- the furnace-chamber, a charging-cylinder for said stoking mechanism disposed at the outside of the furnace-chamber for charging fuel into said retort, a lower half and an upper 5 removable half for said charging-cylinder, a metallic front for said furnace, and means for clamping said front between the upper half of said charging-cylinder and said retort, substantially as described.
- 10 8. The combination with a furnace, of stoking mechanism associated therewith, a metallic front for said furnace, an opening in said front, a retort for said stoking mechanism extending rearwardly from said opening and 15 having a flange at its forward end adapted to fit into and project through said opening so that the face thereof is in alinement with the front face of the furnace-front, a charging-cylinder for charging fuel into said retort, a 20 lower half and a top removable half for said charging-cylinder, each terminating in a flange at its forward end and adapted to be

separably secured to the flanged end of the retort projecting through said opening, said charging-cylinder being disposed entirely 25 without said furnace-front whereby the top half of the charging-cylinder may be removed without moving the lower half thereof, side walls on said retort extending rearwardly and upwardly, the front edge of said walls 30 being in alinement with the inner face of the furnace-front, said furnace-front extending downward between said side walls and the flange on the upper half of said charging-cylinder whereby said front is securely held 35 and prevented from warping, substantially as described.

In witness whereof I hereunto subscribe my name this 22d day of April, A. D. 1903.

FRED A. DALEY.

Correction in Letters Patent No. 733,374.

It is hereby certified that in Letters Patent No. 733,374, granted July 14, 1903, upon the application of Fred A. Daley, of Chicago, Illinois, for an improvement in "Stoking Mechanism," an error appears in the printed specification requiring correction, as follows: In line 125, page 2, the word "and" should read *end*; and that the said Letters Patent should be read with this correction therein that the same may conform to the record of the case in the Patent Office.

Signed and sealed this 4th day of August, A. D., 1903.

E. B. MOORE,

Acting Commissioner of Patents.

[SEAL.]

the furnace-chamber, a charging-cylinder for said stoking mechanism disposed at the outside of the furnace-chamber for charging fuel into said retort, a lower half and an upper 5 removable half for said charging-cylinder, a metallic front for said furnace, and means for clamping said front between the upper half of said charging-cylinder and said retort, substantially as described.

10 8. The combination with a furnace, of stoking mechanism associated therewith, a metallic front for said furnace, an opening in said front, a retort for said stoking mechanism extending rearwardly from said opening and 15 having a flange at its forward end adapted to fit into and project through said opening so that the face thereof is in alinement with the front face of the furnace-front, a charging-cylinder for charging fuel into said retort, a 20 lower half and a top removable half for said charging-cylinder, each terminating in a flange at its forward end and adapted to be

separably secured to the flanged end of the retort projecting through said opening, said charging-cylinder being disposed entirely 25 without said furnace-front whereby the top half of the charging-cylinder may be removed without moving the lower half thereof, side walls on said retort extending rearwardly and upwardly, the front edge of said walls 30 being in alinement with the inner face of the furnace-front, said furnace-front extending downward between said side walls and the flange on the upper half of said charging-cylinder whereby said front is securely held 35 and prevented from warping, substantially as described.

In witness whereof I hereunto subscribe my name this 22d day of April, A. D. 1903.
